(57) **CLAIM**

The ornamental design for a display screen with a virtual pharmacy tutorial graphical user interface, as shown and described.

DESCRIPTION

FIG. 1 illustrates a display screen with a virtual pharmacy tutorial graphical user interface.

FIG. 2 illustrates a second image thereof.

FIG. 3 illustrates a third image thereof.

FIG. 4 illustrates a fourth image thereof.

FIG. 5 illustrates a fifth image thereof.

FIG. 6 illustrates a sixth image thereof.

FIG. 7 illustrates a seventh image thereof.

FIG. 8 illustrates an eighth image thereof.

FIG. 9 illustrates a ninth image thereof.

FIG. 10 illustrates a tenth image thereof.

FIG. 11 illustrates an eleventh image thereof.

FIG. 12 illustrates a twelfth image thereof.

FIG. 13 illustrates a thirteenth image thereof.

FIG. 14 illustrates a fourteenth image thereof.

FIG. 15 illustrates a fifteenth image thereof.

FIG. 16 illustrates a sixteenth image thereof.

FIG. 17 illustrates a seventeenth image thereof.

FIG. 18 illustrates an eighteenth image thereof.

FIG. 19 illustrates a nineteenth image thereof.

FIG. 20 illustrates a twentieth image thereof; and,

FIG. 21 illustrates a twenty-first image thereof.

The appearance of the graphical user interface sequentially transitions between the images shown in FIGS. 1-21. The process or period in which one image transitions to another image forms no part of the claimed design. Any broken lines in the drawings are for illustrative purposes only and form no part of the claimed design. Further, the display screen is shown in broken lines and forms no part of the claimed design.
